UNITED STATES PATENT OFFICE.

JAMES W. BRYCE, OF BLOOMFIELD, NEW JERSEY, ASSIGNOR TO THE TABULATING MACHINE COMPANY, OF ENDICOTT, NEW YORK, A CORPORATION OF NEW JERSEY.

RECORD-CONTROLLED MACHINE.

Application filed September 18, 1925. Serial No. 57,099.

This invention relates to improved apparatus for record controlled or other machines and more particularly to devices for rapidly converting a combination reading into a single reading. Previously in reading combinational hole records the combinational holes were read with the record at rest and, thereafter, the combinational reading was converted into a single reading by mechanical devices to control subsequent machine operation. In other machines a plurality of brushes were employed for reading the combinational record in which case the record could be in motion when the readings were taken.

According to the present invention a single brush can be employed for sensing the records or other representation of a combinational reading while the representation is in motion. This brush controls translating devices which may include set-up contacts for temporarily retaining the combinational reading and afterwards translating the combinational reading into a single reading. The translating operation can be effected by rotary devices whereby high speed operation can be obtained.

These results are accomplished in my present machine by electric devices sensing the combinational holes while the cards are in motion, making set-ups of contacts while the readings of the perforations are being taken and then using those set-up contacts in connection with other devices to obtain a single reading having the same meaning in a device controlled by a single index point perforation as the combinational reading had in machines utilizing combination hole records for control.

40 In the drawings,

Fig. 1 is a side view largely diagrammatic showing the principal features of my invention.

Fig. 2 is a combinational code for numbers.

45 Fig. 3 is a plan view partly in section of the devices in Fig. 1 together with a portion of an accumulator.

Fig. 4 is a front view of the magnet and latching devices shown in the lower half of

50 Fig. 1, the view being taken on the line 4—4.

Fig. 5 is an end view of the bottom half of Fig. 1.

Fig. 6 is a circuit diagram of the electric features of the device.

55 Although my invention may be used in

connection with a variety of card-controlled devices I am for purposes of illustration showing it in connection with a Hollerith type of accumulator, the outline of which is shown at 10 in Figs. 1 and 3.

60 Adjacent the accumulator is a framework supporting most of the parts of the present invention. This framework is not shown in full but is represented by main plate 12 and supplementary plate 14.

65 Mounted on the main shaft 16 is a gear 18 driven by any outside source of power such as motor 20 represented diagrammatically in Fig. 6 which through a belt 22, shaft 24 and gear 26 drives gear 18. Gear 28 fast on 70 shaft 16 through idler gears 30, 32 and 34 drives gear 36 fast on shaft 38 so that shaft 38 rotates at the same speed as shaft 16 both making one revolution per card cycle as does also shaft 40 on which are mounted the make 75 and break cams 42 and 44 (Figs. 1, 3 and 6) which operate the conventional make and break contacts 46 and 48 once per card cycle in the well known manner.

75 Fast on shaft 16 are four disk cams 50 80 each having a small hump 52 and a larger hump 54. Underneath each cam 50 is a co-operating horizontal lever 60 pivoted at 62 and having an upstanding hump 64 directly under shaft 16. Lever 60 is drawn upward 85 by a spring 66. Resting on the free end of lever 60 is a vertical push rod 68.

90 Depending from each lever 60 is a vertical arm 70 having at its lower end a hook 72 and near its middle an armature 74 so placed that arms 70 are drawn to the right when magnet 76 is energized. When magnet 76 is deenergized arm 70 is held to the left by a spring 78. 76 is a double magnet as shown in Fig. 4 and when it is energized all four 95 arms 70 are drawn towards the right.

95 For the purpose of illustration I am using the Peirce code for numbers as shown in Fig. 2. This code comprises 4 index positions A, B, C and D and there may be perforations in one or two of these positions to 100 designate any particular number, as for instance, perforations at A and C mean 3; at B and D mean 4; at B and C the meaning is 8, while a single perforation at B position 105 means 2, etc.

As the cards are fed one by one from the supply magazine 80 between contact brushes 82 and contact blocks 84 (Fig. 6), whenever a brush 82 finds a perforation a circuit is 110

formed as follows, 86 being closed: line 88, contact 46, line 90, brush 82, block 84, line 92, magnet 76 and back through line 94 to 95 which is the other side of the line.

5 There is one brush 82 for each column of index positions on the card and I have shown three columns but more or fewer columns may be used if desired.

10 There is one set of four cams 50 for each card column and each of the four cams corresponds to one code position A, B, C or D.

15 The cards are fed bottom first past the brushes. Consequently the brush on any particular column comes in contact first with the A position, then B, C and D in order. Cams 50 are so set on shaft 16 that the hump 52 on any cam is at its lowest position in contact with hump 64 on lever 60 at the same instant the brush 82 is in contact with the 20 code position to which that cam is correlated.

25 This means that when the brush finds a hole at any position the magnet 76 corresponding to that column will be energized and will attempt to draw all arms 70 to the right. However, only one of the arms 70 can move to the right that being the one which at that instant is depressed as in Fig. 5 by hump 52 on the cam 50 corresponding to 30 that particular arm 70. The other arms 70 not being depressed are prevented from moving to the right by their hooks 72 abutting against the frame member 96. After magnet 76 is deenergized and hump 52 has 35 passed out of contact with lever 60, all arms 70 which were not depressed when 76 was energized remain in the position shown in Fig. 1, whereas the arm 70 which was depressed when magnet 76 was energized is retained in 40 depressed position by its hook 72 engaging frame 96 as in Fig. 5.

45 If as the card passes down past the brush another hole is found in the same column the arm 70 corresponding to that hole is also locked down.

50 The function of the mechanism just described is to control upper and lower contacts 100 and 102. The insulated upper end of rod 68 which rests on the free end of lever 60 acts on spring blade 104 to hold upper contact 100 closed as in Fig. 1 whenever lever 60 is in its higher position. This is the normal position of the parts, with contact 100 closed. Whenever any arm 70 is latched down blade 104 opens contact 100 and closes contact 102.

55 The parts remain in latched position as above described until releasing humps 54 on all cams 50 depress all levers 60 and arms 70 and as 76 is not then energized all arms 70 are returned to normal position by springs 78.

60 The above latching operations have taken place while the holes in the card were passing the brushes and at this point in the card

cycle we have a lower contact 102 closed, and an upper contact 100 open corresponding to each perforation found by the brushes.

65 The remaining part of the cycle will now be described. Fastened rigidly to frame 12 is a plate 106 of bakelite or other non-conducting material. Set into this non-conducting plate are eight metallic plates or strips 108. These plates are arcuate in shape, have irregular outlines substantially as shown in Fig. 1 and are insulated from each other.

70 Fast on shaft 38 is a bent arm 110 carrying two metallic plates 112 and 114. Placed in these plates are four contact brushes designated for convenience A, B, C and D because they correspond to the code positions bearing the same designating letters. This construction means that brushes A and B are connected together electrically, and 75 brushes C and D are likewise connected electrically.

75 As shaft 38 revolves it brings the above brush system into contact with strips 108 immediately after the contacts 100 and 102 have been set up as described, and what then happens can best be understood from diagram Fig. 6.

80 In Fig. 6 are shown diagrammatically three sets of 50 cams, one set for each of the three card columns.

85 The interrelationship of contacts 100, 102, strips 108 and the brushes A, B, C and D is such that as arm 110 sweeps along strips 108 a circuit will be set up in each contact system at the proper time to actuate the differential mechanism of the accumulator in exactly the same manner as if a Hollerith single hole card were being analyzed and accumulated; that is, as shaft 38 revolves the 90 brushes on arm 110 pass the index positions in the order 9, 8, 7, 6, 5, 4, 3, 2, 1, 0, and the set-ups already described insure that any number set up will cause the accumulator clutch 140 to be engaged at the proper differential time to add the correct amount.

95 This can best be understood by considering some special set ups. For instance, in the contact section of Fig. 6 at the left, lower contacts 102 are closed at B and C 100 positions which means 8 in the Peirce code. With these contacts closed the brushes on arm 110 cannot complete a circuit until the 108 position is reached and at that position, shown in the drawing marked 8 at the bottom of Fig. 6, a circuit is formed as follows: from upper side of line 120, through wire 122, contact 100 at D position, wire 124, strip 108 to which 124 is attached, D brush, C brush, strip 108, wire 126, lower contact 102 at C position, lower contact 102 at B position, wire 128, strip 108, B brush, A brush, strip 108, wire 130, upper contact 100 at A 115 position, wire 132, contact 134, accumulator magnet 136 to the other side of line 95. 120

The direction of flow of current is indicated by arrows in the main diagram, and the live wires are shown by heavy lines in the supplementary diagram below.

5 Circuits can be traced in a similar manner in the two other sections of Fig. 6, the middle section reading 4 and the one at the right 3.

10 Contacts 134 and magnet 136 are shown in position in the accumulator in the upper part of Fig. 3 in which also 140 represents the differential clutch device, all of which features are well known in the tabulating art.

15 Although I have shown no printing devices it is well known that the results set up in the accumulator may be printed on record sheets and my invention extends to such use.

20 What I claim is—

1. In a machine controlled by records having combinational holes in columns, in combination with devices controlled in accordance with the meaning of the holes in the records, of means for controlling said devices, said means including a single brush for sensing the combinational hole perforations in each card column.

2. In a machine of the class described, in combination, means for feeding records having combinational holes in columns, analyzing means comprising a single brush for reading the perforations in each card column, and means for setting up contacts corresponding to the holes in each column.

3. In a machine of the class described, in combination, means for feeding records having combinational holes in columns, analyzing means comprising a single brush for reading the perforations in each card column, means for setting up contacts corresponding to the holes in each column, and means for holding said contacts in set up position.

4. The invention set forth in claim 2 in which said analyzing means reads the combinational holes while the cards are in motion.

5. The invention set forth in claim 3 in which said analyzing means reads the combination holes while the cards are in motion.

6. In a machine controlled by records having combinational holes in columns, means comprising a single brush for reading the combinational holes in a card column, a device normally operable by records having only a single hole perforation column, and means to enable the combinational hole readings to operate said device.

7. The invention set forth in claim 6 in which the single brush reads the combinational holes while the cards are in motion.

8. In a machine controlled by records having combinational holes in columns, in combinations, means comprising a single brush

to read the perforations in each column, and devices to set up a single contact corresponding to each hole in the record.

9. The invention set forth in claim 8 in which the perforations are read by the brush while the cards are in motion.

10. In a machine controlled by records having combinational holes in columns, in combination with devices controlled by electric contacts, means comprising a single brush to read the perforations in each card column, means to set up a contact corresponding to each hole in the record, and supplemental contact devices cooperating with said set-up contacts to control said devices.

11. The invention set forth in claim 10 in which said brush reads the perforations while the cards are in motion.

12. In a machine controlled by representations of a certain type, a device normally controlled by representations of a different type and translating mechanism including a single sensing means to enable said first mentioned type of representations to control 90 said device.

13. In a machine controlled by combinational representations, a device normally controlled by single representations and means including a single brush to control 95 said device in accordance with said combinational representations.

14. A combinational index point record controlled machine comprising analyzing means for successively searching index point positions on a controlling record on which characters may be represented according to a combinational index point system in which certain characters may be represented by single index points and others by combinations of index points in which each index point has reciprocal character designating properties with every other index point of the combination, and means controlled by the analyzing means for translating represented characters into time differential equivalents.

15. A combinational index point record controlled machine comprising analyzing means for successively searching, index 115 point positions of each column of a controlling record in which characters may be represented according to a combinational index point system in which certain characters may be represented by single index points and others by combinations of index points in which each index point has reciprocal character designating properties with every other index point of the combination and means controlled by said analyzing 120 means for manifesting characters represented on the controlling records.

16. A combinational index point record controlled machine comprising analyzing means consisting of a single brush for 130

searching each column of a controlling record on which characters may be represented in a column according to a combinational index point system in which certain characters may be represented by single index points and others by combinations of index points in which each index point has reciprocal character designating properties with every other index point of the combination and means controlled by the analyzing means for translating represented characters into time differential equivalents.

17. A combinational index point record controlled machine comprising analyzing means consisting of a single brush for

searching each column of a controlling record on which characters may be represented in a column according to a combinational index point system in which certain characters may be represented by single index points and others by combinations of index points in which each index point has reciprocal character designating properties with every other index point of the combination and means controlled by the analyzing means for manifesting characters represented on the controlling records.

In testimony whereof I hereto affix my signature.

JAMES W. BRYCE.
